CLEANING EQUIPMENT

Chester M. Cain, Amarillo, Tex.

Application August 12, 1940, Serial No. 352,259

3 Claims.

(Cl. 68—22)

This invention relates to cleaning equipment, and more particularly to combined washing and wringing devices for treating, cleaning, and polishing elements, such as chamois and the like cloths, which are sometimes employed for cleaning windshields and polishing car bodies in automobile service stations, the principal objects of the invention being to provide a convenient, relatively economical and highly efficient apparatus of the character noted.

Other objects of the invention are to provide a self-contained washing and wringing device in which the wringing device is motor driven; to provide for energizing the wringing elements of the device at such times as it is desired that the apparatus be operated; to so arrange the apparatus that it may be operated by the foot of the operator, thus leaving the hands of the operator free to manipulate devices being washed and wrung; to provide a unit that is attractive in appearance and that is readily portable for facilitating the service of cars in a service station; to preclude wrapping of the cleaned and wrung devices about the wringing elements of the apparatus; to provide for presenting the wrung cleaning devices in convenient relation to the apparatus for facilitating handling thereof by an operator; to provide for encasing the driving parts or elements of the apparatus relative to the wringing elements of the apparatus; to provide for adjusting the wringing and wringing precluding elements of the apparatus; to provide for servicing the driving elements of the apparatus; and to provide improved elements and arrangements thereof in cleaning equipment apparatus of the character and for the purposes noted.

In accomplishing these and other objects of the present invention, I have provided improved details of structure, the preferred form of which is illustrated in the accompanying drawings, wherein:

Fig. 1 is a perspective view of cleaning equipment embodying the features of the present invention.

Fig. 2 is a detail vertical cross section through the switch and/or control element for energizing and de-energizing the apparatus.

Fig. 3 is a longitudinal vertical substantially central cross-section through cleaning equipment embodying the present invention.

Fig. 4 is a detail vertical transverse section through cleaning equipment embodying this invention substantially on the line 4—4, Fig. 3.

Fig. 5 is a plan view of the cleaning equipment

embodying this invention, parts thereof being shown in horizontal section to more clearly illustrate its construction.

Fig. 6 is a diagrammatic view of a wiring system for energizing the driving elements of the present cleaning equipment.

Referring more in detail to the drawings:

1 generally designates cleaning equipment embodying the present invention, which preferably consists of a horizontally arranged base plate 2 that is preferably provided with swivelled casters or the like 3 at the corners and on the bottom surface thereof.

An end wall 4 is vertically arranged adjacent the end 5 of the base plate, the end wall preferably being of a width less than the width of the base plate to provide platforms or ledges 6 and 7 at opposite sides of the base plate. Side walls 8 and 9 extend from the side edges of the end wall 4 forwardly approximately to the end 10 of the base plate and terminate in inwardly directed flanges 11 and 12 that are preferably of less length or height than the end wall 4. The lower edges of the side and end walls are turned inwardly to provide supporting flanges 13, 14 and 15 that may be suitably secured to the base plate 2 in order to form a rigid mounting for the walls.

16 designates a panel that is of a size and shape to overlie the flanges 11 and 12 of the side walls, the panel and flanges being provided with aligned apertures for receiving fastening devices 17 by which the panel 16 may be removably secured to the side walls and form an enclosure or compartment 18 within the walls.

35 A bottom forming plate 19 for a tank generally designated 20 is horizontally arranged between the end and side walls 4, 8 and 9, the plate 19 preferably being provided with a downwardly turned flange 21 that is suitably secured, as by welding, to the side and end walls above noted. The plate 19 is also preferably arranged approximately at the height of the upper edge of the panel 16, the forward edge of the plate 19 being curved upwardly approximately into the vertical plane of the panel 16 and within the flanges 11 and 12 of the side walls to form an end wall 22 for the tank 20.

The upper portion of the end wall 4 forms the opposite wall for the tank, and the upper portions of the side walls 8 and 9 form the side walls for the tank 20. The end wall 22 of the tank is also curved rearwardly, preferably at approximately the upper end of the flanges 11 and 12, as indicated at 25, Fig. 3, and terminates in a pref-

erably downwardly and backwardly turned lip 26 adjacent one end of the tank.

The upper edges of the side and end walls of the tank are preferably rolled outwardly, as indicated at 27, to provide a relatively blunt edge to protect operators working about the apparatus and enhance the appearance of the equipment.

With the construction thus far described, it is apparent that equipment is provided that includes a lower accessible compartment 18 and an upper substantially open tank 20.

It is contemplated that water or other cleaning liquid 30 is to be supplied the tank 20 to a suitable level and a drain opening 31 is provided in the bottom wall 19 of the tank which opens into an outlet duct 32 arranged in the compartment 18 and extending through the bottom wall thereof, as at 33, for disposing of liquids in the tank, a suitable plug or discharge control 34 being provided for that purpose.

Mounted on the side walls of the tank 20 in transverse alignment is a pair of bearing blocks 35 and 36 that extend upwardly above the edges of the tank, the bearing blocks being secured to the tank walls as by fastening devices 37 and being provided with bearing apertures for receiving the trunnions 38 of a wringer roller 39.

The bearing blocks 35 and 36 comprise side flanges 40 and 41 at their upper ends, the outer edges of the side flanges being connected by a web 42 to form channels 43 for slidably mounting bearing blocks 44. The bearing blocks 44 have apertures 45 to rotatably seat trunnions 46 on a wringer roller 47 that is cooperative with the wringer roller 39. A capping element 48 is mounted on the upper ends of the channel-like bearing blocks, as indicated at 49, and supports an adjusting device 50 for the wringer roller 47, the adjusting device 50 being manipulated to raise and/or lower the wringer roller 47 in relation to the wringer roller 39 in such a manner as to adjust the space therebetween and provide for wringing liquids from cleaning devices of varying thickness or consistency.

Mounted on the cap member 48, as by fastening devices 51, is a stripper plate 52 of approximately the width of the wringer roller 47, which stripper plate depends from the cap member a distance sufficient to present the lower stripping edge 53 thereof approximately at the horizontal median line of the wringer roller 47 and in close, approximate surface, contact therewith.

Assuming that cleaning devices such as chamois skins or cloths have been washed in the tank 20, it is contemplated that they be wrung out by the wringer rollers to remove excess moisture therefrom. In order to facilitate wringing or drying out of the cloths, a driving pulley 55 is preferably mounted on the trunnion 56 of the wringer roller 39 in exterior relation to the tank, as particularly shown in Fig. 4.

A belt 56 that is mounted on the pulley 55 connects with a pulley 57 that is preferably of reduced size, the pulley 57 being mounted at one end 58 of a drive shaft 59 arranged in and projecting from the cabinet or compartment 18. The shaft 59 is rotatably mounted in bearing openings in the upper ends of spaced aligned standards 60 and 61 that are mounted within the compartment 18 and secured to the side walls 8 and 9 thereof by fastening devices 62. Stop collars 63 are secured to the shaft 59 and are engageable with the standards 60 and 61 to prevent play of the shaft laterally in the bearings of the standards. The lower ends of the standards 60 and 61

are preferably mounted on the bottom flanges 14 of the compartment side walls and are preferably additionally secured to the side walls 8 and 9 by fastening devices 64. The shaft 59 is preferably rotated by a pulley 65 that is provided with a belt 66 connecting with a smaller pulley 67 mounted on the drive shaft 68 of a motor 69, the motor in turn being secured to a base 70 that is mounted on the upper face of the base plate 2 in secured relation thereto as by fastening devices 71.

When a service station attendant, for example, is operating the present cleaning equipment, it is convenient to use both hands for rinsing out a chamois cloth and applying it to the wringer roller. To permit the use of both hands of the operator, in the noted operations, the motor is preferably provided with a current supply line 72 that connects with a suitable source of electricity and is also provided with a current conducting line 73 that leads through an opening in a wall of the compartment 18 to a switch 74.

The switch 74 preferably comprises a housing having bearing bosses 75 that are secured to the base plate 2 as by a fastening device 76, one of the ledges 6 and 7 of the base plate being admirably suited for this purpose. An insulated contact 77 is mounted in one of the walls of the switch housing and is arranged for electrical connection with the line 73, as indicated at 78. A spring switch element 79 on the contact 77 is normally arranged in spaced relation to a co-operative switch element 80 supported by an arm 81 that is suitably secured to the switch housing. The contact 80 is connected, as at 81, with the terminal of a current conducting line 82 which constitutes the other lead-in line of the wiring system for energizing the motor 69.

In order to complete a circuit between the switch elements 79 and 80, the wall 83 of the switch housing is provided with a preferably tubular outwardly extending boss 84. A switch operating rod 85 having a head 86 is reciprocably mounted in the boss 84 and is normally held in retracted position relative to the boss by a spring 87 that bears at one end on the wall 83 of the switch housing and at its other end is a cap 88 to which the rod 85 is connected, as indicated at 89, the cap 88 preferably having an inwardly directed sleeve-like end 90 that telescopes over the spring and outer end of the rod 85 to both protect and enhance the appearance of the same.

The wringing elements of the present cleaning equipment are preferably provided with a feed bed attachment 91 to form a guide trough for facilitating feed of chamois skins, cloths, or the like between the rollers 39 and 47. A discharge bed attachment 92 is also provided on the side of the wringer elements opposite the trough 91 to form a platform for receiving the chamois skins after liquids have been wrung from them. The outer edge of the platform 92 is preferably arranged in spaced relation to the lip 26 of the wall 21 to provide a space 93 which may be utilized for feeding the chamois skins back into the tank 20 for re-washing as and when desired.

The pulleys 55 and 57 and the ends of the shafts to which they are connected are preferably housed in a casing 95 that fits thereabout, the inner side edges of the casing being provided with suitable supporting flanges 96 which may be respectively secured to a side wall of the cabinet and tank forming walls of the equipment, as by fastening devices 97, welding or the like,

The operation of cleaning equipment constructed as described is as follows:

The cleaning equipment is rolled to a convenient location and the tank thereof filled with a suitable cleaning liquid. Chamois skins or like cleaning devices may then be applied to the tank for cleaning the same and/or storage. When it is desired to use one of the skins, it is ordinarily too wet for practical use, so the operator merely steps on the cap 88 of the switch, depression of which forces the head of the rod 85 into engagement with the contact 79 to spring the contact into current conducting engagement with the contact 80 and complete the circuit through the lines 73 and 82 to the motor.

The motor lead-in line 72 being connected with a source of current supply, the motor is energized to rotate the pulley 67 and through the belt 66 rotate the pulley 65. The shaft 59 is thus rotated to cause the pulley 57 to move the belt 56 and rotate the pulley 55 which rotates the wringer roller 39. Frictional engagement between the wringer roller 39, the chamois skin and the wringer roller 47 causes the chamois skin to be rolled through between the wringer rollers and wrung out to a substantially dry condition. The tendency of the chamois skin to stick to the wringer roller 47 and wind upon the same is overcome by the plate 51, the lower edge of which separates the chamois skin from the roller 47 and allows the same to drop upon the platform 92. As a matter of practice, more than one chamois skin or the like may be wrung out and chamois skins succeeding the first may be left upon the platform 92 in a convenient position to be picked up by the operator when the first chamois skin has become soiled.

If two or more skins are wrung out together, it is sometimes desirable to adjust the wringer rollers vertically relative to each other in which case the adjusting device 59 may be manipulated to raise the wringer roller 47 relative to the roller 39 and provide more space between the rollers through which the chamois skins may more

easily pass. When the chamois skins have served their purpose, they may be returned to the tank for rewashing and reuse as and when desired.

5 It is apparent, therefore, that the present invention provides a convenient, economical and efficient cleaning apparatus that is attractive in appearance, easily moved from place to place, readily manipulated, simple in construction and 10 easily accessible for necessary repairs.

What I claim and desire to secure by Letters Patent is:

1. In cleaning equipment of the character described, a tank having side and end walls, one 15 of said walls having an inwardly turned upper edge, wringing apparatus mounted on said tank, and a platform arranged adjacent said wringing apparatus for receiving devices wrung thereby, an edge of said platform being arranged adjacent 20 the inwardly turned upper edge of the wall of said tank to form a limited space to allow application of devices to be cleaned to the tank.

2. In cleaning equipment of the character described, a base plate, connected side walls and 25 an end wall arranged in vertical relation to said base plate, a horizontal partition arranged intermediately the height of said side and end walls to define a compartment, a panel removably mounted on said base plate and side walls to 30 provide access to said compartment and forming another end wall, and an extension on said horizontal partition having an inwardly curved upper end cooperative with said partition and walls to form a tank.

35 3. In cleaning equipment of the character described, a base plate, walls arranged in vertical relation to said base plate, certain of said walls having inturned flanges, a horizontal partition arranged intermediately of the height of said 40 walls to define a compartment, and an extension on said horizontal partition having an inwardly curved upper end cooperative with the inturned flanges on the walls to form a tank.

CHESTER M. CAIN.
